Cupps & Harper

Converting Motion.

N° 60,837.

Patented Jan 1, 1867.

United States Patent Office.

JOHN CUPPS, OF CHICAGO, ILLINOIS, AND AMOS R. HARPER, OF GRANDVILLE, MICHIGAN.

Letters Patent No. 60,837, dated January 1, 1867.

IMPROVEMENT IN CONVERTING RECIPROCATING INTO ROTARY MOTION.

The Schedule referred to in these Letters Patent and making part of the same.

TO ALL WHOM IT MAY CONCERN:

Be it known that we, JOHN CUPPS, of Chicago, in the county of Cook, and State of Illinois, and AMOS R. HARPER, of Grandville, in the county of Kent, and State of Michigan, have invented an improved Device for Converting Reciprocating Motion into Equable Continuous Rotary Motion; and we do hereby declare that the following is a full and exact description thereof, reference being had to the accompanying drawings, making part of this specification—

Figure 1 being a side elevation of an apparatus embodying our invention.

Figure 2, a view of a part detached.

Like letters designate corresponding parts in both figures.

Let A A represent the standard or supports of any apparatus for producing reciprocating motion, and converting it into continuous rotary motion, and B a vibratory lever which represents the working beam of a steam engine, or any equivalent intermediate device which receives the reciprocating motion. In the case represented, the beam B is moved by water supplied from a reservoir or head S, the water being let into the buckets T T, on the ends of beams, alternately, through valves or gates g g, opened at the upward stroke by a lifter, h, while at the down stroke a tilter, i, strikes a stop, m, and empties the bucket. Other arrangements for applying water power may be devised, this being shown to indicate how all the water may be utilized without fail or waste. But it is to be understood that the invention which we claim is applicable to many and various powers, whether by hand, by animal, or material or artificial power. The reciprocating motion being communicated to the vibratory beam B, which is secured to a rock-shaft, C, let I be the shaft, and L a balance-wheel or a driver thereon, which are to receive the rotary motion for any purpose whatever. Upon the shaft C, of the beam B, we secure two circular rack-wheels, D E, one larger in diameter than the other, situated at a suitable distance from each other, and each having a segmental rack; one, b, being on the inner edge of the rim of the larger wheel, and the other, a, on the outer edge of the rim of the smaller wheel, substantially as represented. Each rack segment engages respectively with a pinion on the shaft I of the driving-wheel; the rack a of the wheel E with the pinion G, and the rack b of the wheel D with the pinion H, as seen in fig. 2. These pinions are of such a size that one receives as many revolutions or as much motion from the reciprocations of its rack as the other. Both pinions are loose on the shaft I, but are coupled alternately to it by means of couplings O P, which have notches in their faces, abrupt in one direction and oblique in the other, and fit corresponding notches respectively in the faces of the pinions M N. These couplings are prevented from turning on the shaft I, by a vane, R, projecting longitudinally from one side of the shaft and entering notches in the eyes of the couplings. This allows the couplings to slide lengthwise on the shaft I sufficiently to couple the pinions to or uncouple them from the shaft. A spring, Q, between the couplings keeps them spread apart and coupled to their respective pinions in the forward direction, but yields and allows either pinion to have a free movement backward around the shaft I. Thus arranged, when either the rack-wheel D or E turns backward in relation to the motion of the driving shaft, I, its pinion disengages itself from its coupling and does not turn the shaft; but when the rack-wheel moves forward it turns the shaft and the driving-wheel. So both wheels D E only move the shaft and driving-wheel forward; and since they act alternately in immediate succession, it follows that the shaft I and the wheel L continually move forward; and since the rack-wheels produce uniform motion, the rotary motion produced thereby is equable and constant, and there are no dead-points. In this and other respects it is much superior to cranks and other devices for the purpose. Any style of clutch may be used instead of the notched couplings described; and different arrangements of these may be employed if desired, all that is essential being to couple and uncouple alternately as the directions of the reciprocating motion follow each other. Another set of racks, c d, on the other side of the wheels D E, may be used to operate on another driving shaft which would be mounted in the bearings f f; and other rack-wheels might be used on the same shaft C, and thus various motions and different in speed may be produced from the reciprocations of one beam B, or its equivalent. The uses and adaptations of this invention are many and various.

What we claim as our invention, and desire to secure by Letters Patent, is—

The employment of two rack-wheels or segmental circular racks, in combination with two pinions on the driving shaft, arranged so as to be coupled alternately thereto in such a manner as to produce continuous rotary motion in one direction, substantially as and for the purpose herein specified.

JOHN CUPPS,
AMOS R. HARPER.
